(57) **CLAIM**

The ornamental design for a clamp for securing a ladder to a fascia, as shown and described.

DESCRIPTION

FIG. 1 is a top perspective view for a clamp for securing a ladder to a fascia showing my new design;

FIG. 2 is a left side view thereof;

FIG. 3 is a right side view thereof;

FIG. 4 is a rear side view thereof;

FIG. 6 is a front side view thereof;

FIG. 7 is a bottom side view thereof; and,

FIG. 8 is a bottom perspective view shown in an environment of use.

The broken lines in FIG. 8 depict environmental subject matter only and form no part of the claimed design.

1 Claim, 6 Drawing Sheets
